CLAIM

The ornamental design for a pet toy ball, as shown and described.

DESCRIPTION

FIG. 1 is a top-facing perspective view of the pet toy ball showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing of a carabiner and its circular base attached to the pet toy ball depict environmental structure and form no part of the claimed design. The remaining broken lines depict portions of the pet toy ball and form no part of the claimed design.
